UNITED STATES PATENT OFFICE.

FRANK THEODORE WILLIAMS, OF MERIDEN, CONNECTICUT, ASSIGNOR TO
THE EDWARD MILLER & COMPANY, OF CONNECTICUT.

LAMP-BURNER.

SPECIFICATION forming part of Letters Patent No. 659,333, dated October 9, 1900.

Application filed July 18, 1900. Serial No. 23,991. (No model.)

To all whom it may concern:

Be it known that I, FRANK THEODORE WILLIAMS, a citizen of the United States, residing at Meriden, Connecticut, have invented certain new and useful Improvements in Lamp-Burners, of which the following is a full, clear, and exact description.

My invention relates to lamp-burners; and my object is to improve the construction of the same. One of my principal objects is to provide a central-draft burner in which the wick burns on its outer circumference and is substantially protected at its top with a gas-generating space within the inner circumference of the wick and at its upper portion to supply the gas so generated to the flame.

In the drawings, Figure 1 shows the preferred embodiment of my invention in central vertical section, the spreader being shown in side elevation and the parts being in their raised position. Fig. 2 shows the same parts in the lowered position, the spreader being shown in section and partly broken away; and Figs. 3 and 4 show modifications in the raised position.

In the above preferred embodiments of my invention 1 represents the fount of a lamp having an outer wick-tube 2 and an inner wick-tube 3, between which may move a wick 4.

5 is a wick-rod or other device for raising and lowering the wick. Such a wick-raising device is well known in the art and is therefore not herein particularly shown or described. Within the inner wick-tube is located a wall 6, preferably cylindrical, as shown. I prefer to allow this wall to freely move up and down within the inner wick-tube; but this construction is not in all cases essential, as will be explained hereinafter. In Figs. 1, 2, and 3 I have shown this wall as in the form of a cylinder, which is freely movable in a vertical direction.

7 is a spacer between the inner wick-tube and the wall 6 for holding the wall slightly away from the inner wick-tube. In Figs. 1, 2, and 4 this spacer is formed by an inturned flange at the top of the inner wick-tube; but in Fig. 3 it is formed by a flange on the movable wall.

8 is a ring of thin metal resting on top of

the wick to protect the top of the wick from the flame and at the same time act as an extinguisher when the wick is lowered, as shown in Fig. 2. This extinguisher is preferably 55 formed by an outwardly-extending flange from the top of the cylindrical wall 6.

In Figs. 1 and 2, 9 is a so-called "spreader," which is slipped down inside of the cylindrical wall 6 and may rest on an inturned 60 flange 10. In Fig. 4 I have shown the spreader and wall made in one piece, the portion 9^a constituting the spreader and the part 9^b the wall.

As shown in Fig. 4, the extinguisher 8 may 65 be either attached to the wall 9^b, so that the wall, spreader, and extinguisher move up and down at the same time, or the wall and spreader may be fixed, and the extinguisher may alone move.

70 In Fig. 3 the extinguisher is formed by a flange at the top of the cylindrical wall 6. 13 is a rod fixed inside of the inner wick-tube and carrying a preferably removable stop 14 to limit the upward movement of the spreader 75 and therefore of the extinguisher.

When the parts are in the raised position, (shown in Figs. 1, 3, and 4,) the spacer 7 forms, with the wall 6, a gas-space 11 at the inside of the upper portion of the wick, in which 80 space gas will be generated. One of these parts, the extinguisher or wall 6, or both, as in Figs. 1 and 2, may be perforated for the escape of the gas from the space 11 to the inner side of the flame. I prefer not to have 85 the perforations in the extinguisher extend over the top of the wick, because if they did the top of the wick would become charred, and the charred particles would soon clog up these perforations. In the present embodiment I have shown the perforations as entirely within the inner circumference of the wick, and this is the preferred construction; but I do not desire to limit myself to this feature.

95 I prefer to have the gas-space 11 substantially air-tight—that is, substantially closed to the entrance of the air-supply passing up through the inner tube—but this is not essential in all cases. When the parts are in the 100 position shown in Figs. 1, 3, and 4, the flame will burn at the outside of the wick, and the

heated metal parts, together with the heat of the flame, will generate gas in the gas-space 11. This gas will pass up through the perforations 12 and mingle with the gas generated from the outside of the wick, thus providing an additional supply for the flame. In this way I have provided a burner which will give a brilliant and steady flame. The construction is cheap, and the burner may be easily taken apart for cleaning and reassembled by any unskilled person.

I am aware that many changes may be made in the construction herein disclosed without departing from the spirit of my invention, and therefore I do not desire to be limited to the particular embodiments herein shown and described.

What I claim is—

1. In a lamp-burner in combination, an inner and an outer wick-tube, an extinguisher adapted to rest on top of a wick and be moved up above said outer tube, a wall smaller than and located inside of said inner tube, a spacer to hold said wall away from said wick and form, with said wall, a gas-space at the inside of said wick, one of said parts being perforated to allow the escape of gas from said space to the flame.

2. In a lamp-burner in combination, an inner and an outer wick-tube, an extinguisher adapted to rest on top of a wick and be moved up above said outer tube, a cylindrical wall smaller than and located inside of said inner tube, a spacer below said extinguisher and between said wall and inner tube to form, with said wall, a gas-space at the inside of said wick, said extinguisher being perforated to allow the escape of gas from said space to the flame.

3. In a lamp-burner in combination, an in-

ner and an outer wick-tube, an extinguisher adapted to rest on top of a wick and be moved up above said outer tube, a cylindrical wall smaller than and located inside of said inner tube, said wall being fixed to said extinguisher and movable therewith, a spacer below said extinguisher and between said wall and inner tube to form, with said wall, a gas-space at the inside of said wick, one of said parts being perforated to allow the escape of gas from said space to the flame.

4. In a lamp-burner in combination, an outer and an inner wick-tube, a cylindrical wall smaller than and vertically movable within said inner tube, a spacer between said inner tube and wall, an extinguisher-flange on said wall and extending out over and resting on said wick and adapted to be raised above said outer tube and provided with perforations extending within the inner wick-tube.

5. In a lamp-burner in combination, an outer wick-tube, an inner wick-tube having an inwardly-turned flange at the top, a cylindrical wall smaller than and vertically movable within said inner tube and flange, an extinguisher-flange on said cup and extending out over and resting on said wick and adapted to be raised above said outer tube and provided with perforations within the inner wick-tube, and a spreader adapted to rest within said cup and provided with perforations above said extinguisher-flange.

Signed at Meriden, Connecticut, this 16th day of July, 1900.

FRANK THEODORE WILLIAMS.
